UNITED STATES PATENT OFFICE.

DAVID BAIRD MACDONALD, OF LEICESTER, ENGLAND.

TOE-PUFF AND LIKE STIFFENER FOR BOOTS AND SHOES.

1,345,944.

Specification of Letters Patent.

Patented July 6, 1920.

Application filed March 2, 1920. Serial No. 362,859.

To all whom it may concern:

Be it known that I, DAVID BAIRD MACDONALD, subject of the King of Great Britain, residing at Leicester, in the county 5 of Leicester, England, have invented certain new and useful Improvements in or Relating to Toe-Puffs and like Stiffeners for Boots and Shoes, of which the following is a specification, reference being had 10 therein to the accompanying drawing.

This invention relates to toe-puffs and like stiffeners for boots and shoes and concerns chiefly those of the kind composed of textile material impregnated or coated with 15 gum or other stiffening agent.

The invention has for its object to put upon the market a stiffening article which will be ready for immediate use and will not require softening prior to insertion into 20 a boot or shoe upper. The toe-puff or stiffener comprehended by the present invention will be adapted to be placed in an upper while in a soft or pliable condition and after being lasted will set hard and firm.

25 The invention consists of a toe-puff or other stiffener comprising a face layer, a back layer, one or more intermediate layers of reticulated material coated or impregnated with a stiffening agent in solution in 30 a solvent of volatile character, and with or without one or more middle layers of porous, absorbent or other suitable material adapted to serve as a carrier for the stiffening agent.

35 The invention also includes a method of packing the improved stiffeners as will be hereinafter described.

In particularly describing the invention reference will be made to the accompanying 40 drawings in which:—

Figures 1 and 2 show different forms of a toe-stiffener.

Fig. 3 shows a stiffener formed of graded layers.

45 Figs. 4 and 5 illustrate methods of making stiffeners wherein the thickness is varied.

Fig. 6 shows in plan an open tin or container with the stiffeners packed therein.

50 Fig. 7 shows, in perspective, a device used in connection with the packing of the stiffeners.

The views in the drawings are shown by way of example, and in Figs. 1 and 2 the

layers are partly separated to show the same 55 more clearly.

According to one example a stiffener, such as a toe stiffener, comprises (Fig. 1) a face layer *a* of nonporous and preferably smooth surface material, a back layer *b* of porous, 60 non-porous or absorbent material having a cellular, pitted or rough surface, and one or more intermediate layers *c* of reticulated material coated or impregnated with a stiffening agent in solution in a solvent of 65 volatile character.

In the example shown in Fig. 2, the stiffener comprises a middle layer *d* of porous, absorbent or other suitable material adapted to serve as a carrier for the stiffening agent, one or more layers *c* of reticulated material applied to each side of the middle layer or carrier *d*, and a layer of covering material applied to the reticulated material so as to form the face *a* and back 75 *b* of the article, the middle layer *d* being impregnated or coated with a stiffening agent in solution in a solvent of volatile character.

The layers are preferably formed of textile material, the face layer *a* being thin, 80 smooth and constituting the upper or outer face of the stiffener while the back layer *b* may be comparatively thicker and constitutes the underside. The intermediate reticulated layer or layers *c* is or are also preferably of textile character and serve as a binding medium for the stiffening agent.

In a concrete form of the invention the face layer *a* is made of a textile material 90 such for example as white croydon, linen or like material preferably dressed or filled so as to be non-porous, the thicker layer *b* for the back is made of duck, the reticulated layers *c* are made of muslin or equivalent, 95 and when used, the middle layer or carrier *d* is made of swansdown or a jute fabric such as hessian.

In making a stiffener composed of layers such as illustrated in Fig. 1, the stiffening agent is applied by being spread upon the back of the face layer *a* upon which is then placed a reticulated layer *c* and a further layer of the stiffening preparation is spread thereon, this operation being repeated with 100 a further layer or layers of reticulated material *c* and the stiffening agent until the desired thickness has been obtained then 105

finally the layer of backing material *b* is applied.

In the case of the stiffener shown in Fig. 2, the stiffening agent may be applied by being spread upon both sides of the middle layer *d* upon each side of which is then placed a muslin layer *c* and this may also be given a coating of the stiffening agent. A further muslin layer *c* is then applied 10 on each side and is coated with the stiffening agent after which the face and back layers *a* and *b* are applied to the respective sides. Or alternatively the article may be made up by commencing with the back or 15 face layer *b* or *a*, spreading on this a coating of the agent, then applying thereto a reticulated layer *c*, spreading on this a coating of the agent and applying another reticulated layer, spreading on this a coating 20 of the agent and applying thereto the middle layer *d*, then similarly applying two more reticulated and coating layers and finally, after coating the last reticulated layer with the agent, applying the face or back layer 25 as the case may be.

The stiffening agent holds the superposed textile layers together and is itself bound together by the reticulated intermediate layers into the pores or openings of which 30 it passes.

Instead of making the face and back layers of different materials as above suggested, they may be made of the same material, for example, they may both be made 35 of duck or both of white croydon or some other material suitable for the purpose. Preferably however, the face layer is composed of a textile material having a smooth surface and of non-porous character, and 40 it is an essential feature that the middle layer or carrier, when used, is of absorbent, porous or similar character adapted to become impregnated with and hold the stiffening agent.

45 The stiffening agent used is preferably one containing celluloid in solution and is applied in a liquid or semi-liquid condition for example in the form of a viscous paste. The purpose of the middle layer or carrier 50 is to absorb or otherwise retain the moist stiffening agent and prevent the latter running or oozing out at the edges such as when the stiffeners are packed, one on top of another. For instance by using a textile material such as hessian or other jute or like 55 fabric, coarse canvas, felt, coarse duck swansdown or other material which is porous or absorbent to compose this layer, the same becomes impregnated with the agent 60 and so retains it. Similarly, where a middle layer such as *d* is not used, it is the purpose of the back layer *b* to absorb or otherwise retain the moist stiffening agent. On the other hand it may be found that a middle layer or a back layer composed of a ma-

terial which is non-porous or non-absorbent but has a cellular, or pitted or rough surface which will hold the stiffening agent will answer the purpose. A good combination may consist of a porous or absorbent 70 middle layer, and a back layer of a non-porous material which latter is adapted by reason of its rough, cellular or pitted surface to hold the agent. In this case the back layer will assist the middle layer in retaining the moist stiffening agent. The face layer may, for example in a vamp stiffener, be made of similar material and also serve to retain the agent.

As a further means to prevent the flow 80 of the moist stiffening agent, the latter may have mixed with it an inert material such for example as shoddy, vegetable charcoal, fibrous cotton, wool or leather, the purpose being to compact or bind the agent so that 85 while it is in a moist condition it is restrained from flowing or running out from between the layers composing the puff or stiffener.

The puffs or stiffeners may be made up of 90 layers of the material employed which are cut out to the shape desired before being assembled such as shown in Figs. 1 and 2. Or the materials in sheet form may be assembled and combined with the stiffening agent 95 and be afterward cut to produce the articles. The latter method has an important advantage in so far that the operation of cutting out the puff or stiffener while the agent is moist presses the edges of the layer together 100 and seals up the article all around its edge thereby preventing escape of the stiffening paste.

It is also a feature of the invention that 105 for the purpose of varying the thickness of the article, graded layers of material may be used, that is to say instead of the various layers of material composing the stiffener being uniform in size (in which case the article is of uniform thickness) the said 110 layers may be graduated in size so that the article is made thinner at its edge. For instance the stiffeners shown in Figs. 1, 2 and 3 are formed with a rear thin edge *e* by using a face layer *a* of smaller size than the 115 next layer *c* which in turn is smaller than the layer underneath it. These different sized layers are placed together level at the front *f* so that in the article produced there is a less number of thicknesses at the opposite edge *e*. Or the same effect may be produced 120 by gradually reducing the size of the layers from the face layer to the back layer, or from the middle layer to the back and front layers. By varying the sizes of the layers 125 and arranging the position of the smaller layer or layers on the larger, any desired part of the edge of the article may be made thin by reducing the number of layers at this locality while the greater number of 130

layers in the center of the article gives stiffness where required. This method of grading may also be used when the layers of material are superposed before the articles are

5 cut therefrom the said layers being set back from one another at the edge or edges so that when the articles are cut out the corresponding edge or edges will be thin.

For instance as shown in Fig. 4 the layers 10 *a*, *c*, and *b* in strip form are of different width and placed level at one side so that when the stiffeners are cut out as represented they will be thin at the back edge. Fig. 5 shows the same method carried out with 15 wider material and the cutting of two stiffeners having a front edge *f* of full thickness and a thinner rear edge *e*.

For light and thin puffs or stiffeners it is sufficient to either use one middle layer or 20 carrier, or to omit the middle layer as herein described, but for stiffer puffs and stiffeners such for example as those used for men's boots and shoes the article covered by this 25 invention may contain two or more middle layers of the kind herein referred to. When two or more of the carrier layers are used they may be placed together after being coated with the agent, or one or more of the reticulated layers may be interposed between 30 the said carrier layers to bind the stiffening agent.

It is intended to use a stiffening agent 35 which will upon the evaporation of a spirituous medium therein, set hard and stiff, and to pack the stiffeners while they are in a moist and pliable condition, in tins or other suitable containers which are adapted to keep the articles in a moist condition so that when required for use they may be 40 taken out and are ready for immediate insertion into boot and shoe uppers without requiring to be softened. During the time the articles remain packed the middle layer or the back or both prevents the moist 45 stiffening agent from running out.

In packing the articles they are placed closely one upon another and preferably in alternating reversed position as represented in Fig. 6, to facilitate separation.

50 To further facilitate separation of the articles when they are unpacked and required for use, there may be employed for packing purposes a band or strip or equivalent which is passed to and fro between the superposed articles so that between each 55 pair of adjacent articles there is located a portion of the band or strip. The band or strip is preferably of plicate form, as shown by way of example in Fig. 7, so that a stiffener can be placed between each fold, in 60 which case it will be understood each article is separated by those on each side of it by the intervening length *g* of the band. When the superposed articles with the band or 65 strip combined are packed, they lie close

together, but upon removal from the tin or container, by pulling upon the opposite ends of the band and wholly or partially straightening it out the whole of the articles are separated from each other.

70

The band or strip is preferably made of metal such as tin for example, and is folded to shape prior to use, the folded parts being left open a sufficient distance to permit of the ready insertion of the articles between 75 its folds. In loading such a band or strip it is laid or held in a horizontal position and stiffeners are placed in position in the open folds, then the band is turned over and the open folds on the other side are filled, after 80 which the whole is closed endwise and placed in the tin or container. By providing with a definite number of folds, counting of the articles may be rendered unnecessary as all the operator need do is to fill 85 the band on both sides. Thus the packing band may serve as a counter.

When made of metal or any equivalent stiff material each fold may be made square as represented at *h* or of some other shape which 90 will obviate, when the band is closed upon the positioned articles, squeezing said articles on the edge and the material employed is such that will allow of the band being extended by pulling upon its ends when 95 the articles are to be removed.

Alternatively to forming the band or strip of metal or equivalent it may consist of a strip of tape, paper, or some other pliable material this being combined with the 100 articles as they are placed in succession one upon another. A band of this character when combined with the packed articles serves to separate them upon being pulled out straight after removal of the pile from 105 the container.

Or by leaving the packed pile of articles in the container and pulling the top end of the band or strip upward, the articles may be separated and removed one at a time. 110

It is intended that the band or strip shall be of such width comparatively to that of the articles as to enable separation of said articles to be readily effected.

Alternatively however, two or more narrower bands may be used with each pile of articles instead of one band.

Instead of using a flat band or strip I may use a length of wire, string, twine, paper twine or the like for the purpose aforesaid. 115

What I claim then is:—

1. A stiffener for use in the herein described manner, comprising a face layer, a back layer, a plurality of intermediate layers of reticulated material coated or 120 impregnated with a stiffening agent and a middle layer of porous, absorbent or like material adapted to serve as a carrier for the stiffening agent, substantially as described.

125

130

2. A stiffener for use in the herein described manner, comprising a middle layer of porous, absorbent or like material impregnated or coated with a stiffening agent, 5 a layer of reticulated textile material applied to each side of the middle layer, a layer of textile covering material applied to the reticulated material to form the face of the article and a layer of material having a 10 pitted or roughened surface and applied to the reticulated material to form the back of the article.
3. A stiffener for use in the herein described manner comprising a central filling 15 portion composed of a plurality of layers of porous or absorbent material impregnated with a stiffening agent a layer of textile covering material applied to the central filling portion to form the face of the article 20 and a layer of textile material having a pitted or roughened surface and applied to the central filling portion to form the back of the article.
4. A stiffener for use in the manner de-
scribed, consisting of a pad having a face 25
layer of impervious textile material, a back
layer of textile fabric, and a plurality of in-
termediate layers, one at least of which is
of soft porous textile fabric impregnated
with a plastic stiffening agent and the 30
other of reticulated textile fabric adapted
to be penetrated by the stiffening agent.
5. A stiffener for use in the herein de-
scribed manner, comprising a middle layer
of swansdown, impregnated or coated with 35
a stiffening agent, layers of muslin applied
to each side of the middle layer a face layer
of croydon and a back layer of duck, sub-
stantially as described.

In testimony whereof I affix my signa- 40
ture in presence of two witnesses.

DAVID BAIRD MACDONALD.
